UNITED STATES PATENT OFFICE.

CHARLES A. LAPWORTH, OF WEST BRIDGEWATER, MASSACHUSETTS, ASSIGNOR TO THE LAPWORTH WEBBING COMPANY, OF BROCKTON, MASSACHUSETTS.

DESIGN FOR AN ELASTIC FABRIC.

48,473.

Specification for Design.

Patented Jan. 18, 1916.

Application filed October 7, 1915. Serial No. 54,679. Term of patent 7 years.

To all whom it may concern:

Be it known that I, CHARLES A. LAPWORTH, a citizen of the United States, residing at West Bridgewater, in the county of Plymouth and State of Massachusetts, have invented a new, original, and ornamental Design for Elastic Fabrics, of which the following is a specification, reference being had to the accompanying drawing, forming part thereof.

The figure is a plan view of a portion of the fabric showing my design.

The body of the fabric contains a series of transverse zig-zag rows which interlock

with each other and extend to the longitudinal margins of the fabric, which margins have longitudinal, parallel, rounded edges ornamented by small oblong protuberances arranged in transverse rows.

I claim—

The ornamental design for an elastic fabric as shown and described.

In testimony whereof, I have hereunto subscribed my name.

CHARLES A. LAPWORTH.
